(57) **CLAIM**

The ornamental design for a fishing jig head, as shown and described.

DESCRIPTION

FIG. 1 is a perspective view of a fishing jig head that shows our new design.

FIG. 2 is a right side view of the fishing jig head shown in FIG. 1. (The left side view of the fishing jig head is a mirror image and not shown.)

FIG. 3 is a top view of the fishing jig head shown in FIG. 1.

FIG. 4 is an alternate top view of the fishing jig head shown in FIG. 1 with the blade removed.

FIG. 5 is a front view of the fishing jig head shown in FIG. 1.

FIG. 6 is a rear view of the fishing jig head shown in FIG. 1; and,

FIG. 7 is a bottom view of the fishing jig head shown in FIG. 1.

The broken lines in the Figures do not form a part of the claimed design.

1 Claim, 6 Drawing Sheets
